DESIGN FOR A CHRISTMAS ORNAMENT

Kenneth G. Troxell, Easton, Pa.

Application June 6, 1947, Serial No. 139,499

Term of patent 14 years

(Cl. D29—1)

To all whom it may concern:

Be it known that I, Kenneth G. Troxell, a citizen of the United States, residing at Easton, in the county of Northampton and State of Pennsylvania, have invented a new, original, and ornamental Design for Christmas Ornament, of which the following is a specification, reference being had to the accompanying drawing, forming part thereof.

In the drawing:

Fig. 1 is a side elevational view of a Christmas ornament showing my new design.

Fig. 2 is a top plan view of the same.

I claim:

The ornamental design for a Christmas ornament, as shown.

KENNETH G. TROXELL.
